UNITED STATES PATENT OFFICE.

SYLVANUS DECKER AND FRAZEE AYRES, OF RAHWAY, NEW JERSEY.

IMPROVEMENT IN WASHING-MACHINES.

Specification forming part of Letters Patent No. 117,265, dated July 25, 1871.

To all whom it may concern:

Be it known that we, SYLVANUS DECKER, of the city of Rahway, in the county of Union and State of New Jersey, and FRAZEE AYRES, also of the city, county, and State aforementioned, have invented certain Improvements in Washing-Machines, of which the following is a specification:

Our invention relates to an improvement in that class of washing-machines wherein the cleansing is effected by means of a dasher moving in a box and agitating and compressing the fabric to be cleansed; and consists in the combination of a perforated dasher with perforated side pieces, the side pieces being pivoted to the body of the machine and having their upper edges attached by rods to the lever or handle of the dasher, thereby acquiring a motion corresponding with the motion of the dasher, though in an opposite direction, the object being by this motion to induce agitation in the mass of clothing and water in the machine, and, by the alternate compression of the masses of clothing between the dasher and each of the side pieces, to force the water through the clothing, thereby removing all dirt from the same.

The accompanying drawing represents a cross-section of the machine, showing its general construction.

A is the box forming the body of the ma-

chine, which should be substantially constructed and water-tight. B is the perforated dasher, operated by the lever C. D D are the perforated side pieces, which are pivoted at a a to the ends of the box and connected at b b, by the rods E E, to the lever, the rods being fastened to the lever above the axle F, which sustains the lever and serves the purpose of a fulcrum.

In operating the machine the box should be partly filled with water and the fabric to be cleansed placed between the dasher and side pieces; then, on operating the lever, motion is communicated to the dasher and side pieces, the whole mass in the machine is agitated, and, the clothing being alternately compressed on each side of the dasher, the water is forced through it and all dirt removed.

We claim as our invention—

The combination of the dasher B with the movable side pieces D D, when both dasher and side pieces are attached to and operated by the lever C, substantially as and for the purposes hereinbefore set forth.

SYLVANUS DECKER.
FRAZEE AYRES.
